Brown & Hall.

UNITED STATES PATENT OFFICE.

LE ROY S. WHITE, OF WATERBURY, CONNECTICUT.

GARMENT-SUPPORTER.

SPECIFICATION forming part of Letters Patent No. 364,387, dated June 7, 1887.

Application filed January 10, 1887. Serial No. 223,843. (No model.)

To all whom it may concern:

Be it known that I, LE ROY S. WHITE, of Waterbury, in the county of New Haven and State of Connecticut, have invented a new and 5 useful Improvement in Garment-Supporters, of which the following is a specification.

My invention relates to that class of garment-supporters which consist of a stirrup or bail-like portion serving for the attachment of 10 a strap, and converging arms, which are brought near together at the opposite end of the device, and which are elastic, so that they hold tightly upon the stocking or other garment wedged between them. Supporters of 15 this class have usually been stamped or blanked out from sheet metal or made of wire, and heretofore, when made of wire, the wire has most frequently been continuous throughout the two converging arms and the bend, whereby 20 they are joined at the bottom of the device or at its ends, and have been lapped and secured by solder or a band in the stirrup or bail-like portion in the top.

The object of my invention is to provide for 25 readily joining the ends of the wire at the smaller end of the device, without the employment of any solder, in such manner as to improve the appearance of the device.

The invention consists in a garment-supporter composed of a piece of wire bent to 30 form a stirrup or bail-like portion at the top of the device, and converging arms, the ends of the wire forming the extremities of the arms and having lateral offsets or projections, and a 35 seamless cap of sheet metal folded or closed over and concealing the extremities of the arms and inclosing the lateral offsets or projections.

In the accompanying drawings, Figure 1 is 40 a view of a complete device embodying my invention. Fig. 2 represents the extremities of the two converging arms and a sectional view of the cap whereby they are confined. Fig. 3 represents a transverse section on the 45 plane of the dotted line x x , Fig. 2; and Figs. 4 and 5 represent one of the converging arms in planes at right angles to each other, showing how its end is slightly flattened to form lateral offsets or projections.

50 All the figures are drawn upon a scale larger than actual size, and Fig. 1 is upon a scale smaller than the remaining figures; and in all

the figures similar letters of reference designate corresponding parts.

The device comprises a stirrup or bail-like portion, A, and two arms, B, which extend therefrom in the same direction, and which converge downward to their lower extremities. The arms throughout the lower portion of their length converge slightly, or they may, 55 when the device is not in use, lie substantially parallel; and when a stocking or other garment or fabric is wedged between these arms it serves to spread them, and the resistance which they oppose to such spreading movement causes them to bite or clamp securely 60 upon the fabric and hold the same from accidental disengagement from the supporter. A strap is usually sewed to the stirrup or bail-like portion A, and may be attached to some 65 part of the garments above.

The ends of the wire are at the two extremities of the converging arms B, and are secured and confined together by a seamless cap, C, which is made of sheet metal and is closed 70 over the extremities of the arms. The cap C may be struck up, by means of a punch and die, of soft brass or other metal. The metal from which the cap is made will be softer than 75 the steel wire forming the converging arms B, 80 and by pressure on the cap between dies, after the ends of the wire have been introduced within it, the metal of the cap will be closed tightly upon the ends of the wire, and they will be secure from disengagement from the 85 cap. To make the hold of the cap upon the ends of the wire more secure, the ends of the wire may be formed with lateral offsets or 90 projections, which may be produced by flattening the extremities of the wire, as shown at b, and the cap is closed upon the arms B above such lateral offsets or projections, and, indeed, by closing the cap C upon the ends of the wire the offsets or projections formed by flattening the wire may be caused to indent 95 themselves into the metal of the cap, as best shown in Fig. 3.

By my invention it will be seen that a single thickness of wire is used throughout the entire stirrup or bail A and arms B, and the 100 cap C serves to properly confine the ends of the wire and imparts a neat finish to the article.

I am aware that it has been proposed to

make a towel-holder of substantially the form of the device shown in my drawings, and to secure the ends of the wire by casting upon them a ball of metal. Although the ends of the wire might be properly held by such ball of metal, the heat of the molten metal when run around them might have a tendency to reduce the temper of the converging arms or render them soft or annealed, and it is believed that the ends may be secured by a sheet-metal cap at a less cost than by casting a ball of metal upon them.

What I claim as my invention, and desire to secure by Letters Patent, is—

The garment-supporter herein described, consisting of a piece of wire bent to form the stirrup or bail A and the converging arms B, the ends of the wire forming the extremities of the arms and having lateral offsets or projections, and a seamless cap, C, of sheet metal, folded or closed over and concealing the extremities of the arms and inclosing the lateral offsets or projections, substantially as herein set forth.

LE ROY S. WHITE.
